UNITED STATES PATENT OFFICE.

WILLIAM A. ROWE, OF DETROIT, MICHIGAN, ASSIGNOR TO AMERICAN BLOWER COMPANY, OF DETROIT, MICHIGAN, A CORPORATION OF MICHIGAN.

FAN WHEEL AND METHOD OF MAKING SAME.

Application filed March 17, 1922. Serial No. 544,477.

To all whom it may concern:

Be it known that I, WILLIAM A. ROWE, a citizen of the United States, residing at Detroit, in the county of Wayne and State of Michigan, have invented certain new and useful Improvements in Fan Wheels and Methods of Making Same, of which the following is a specification, reference being had therein to the accompanying drawing.

10 This invention relates to improvements in centrifugal fans, and more particularly to an improved fan wheel of the multi-bladed type and method of making same.

15 The object of the invention is to provide an improved small size fan wheel of the class referred to that will be sufficiently strong and rigid and which can be produced at low cost.

20 The invention, with other objects and advantages thereof, and the particular construction, combination and arrangement of parts comprising the same will be understood from the hereinafter contained detail description, when considered in connection with the accompanying drawings, forming 25 part hereof, and illustrating one embodiment of the invention.

In the drawings:

20 Figure 1 is a perspective view of a fan wheel constructed in accordance with the present invention.

Fig. 2 is a similar view prior to the formation of the blades.

Fig. 3 is a prospective view of the blank of metal from which the fan wheel is formed.

25 Fig. 4 is an elevation showing the same slotted prior to pressing out the blades.

Fig. 5 is a longitudinal section, on an enlarged scale, through a portion of the rim of the wheel.

40 Figs. 6 and 7 are detail transverse sections, on lines 6-6 and 7-7 of Fig. 5.

Fig. 8 is a detail plan view of a portion of the wheel.

45 In accordance with the present invention a fan wheel of integral cup-shaped formation comprising a rim part and a plate or disk at one end thereof is provided by pressing or drawing the same out from a single continuous flat sheet of metal, the blades of the wheel 50 being afterwards formed by bending portions of the rim therefrom.

The particular construction illustrated in the drawings, by way of example, comprises a cylindrical rim part or drum 1, a plate or

disk 2 at one end thereof, an outwardly extending annular flange or flared portion 3 at its opposite end, and blades 4, the same being an integral structure pressed or drawn out from a continuous flat round sheet of metal *a*, illustrated Figure 3. Figure 2 shows the structure after the pressing or drawing operation prior to the formation of the blades. In the forming of blades 4, the rim part 7 is provided intermediate its edges with a series of equally spaced transverse slits 5, and series of longitudinal parallel slits 6 extending from the ends of the transverse slits 5 approximately midway between the transverse slits. The portions bounded by the series of slits 5-6, are then bent therefrom, and said portions and the adjacent portions of the intermediate supporting strip portion 7 are shaped to give the blades the desired curvature and inclination, the supporting strip portions 7, being slightly stretched or shaped as shown, see particularly Figure 6, the stretching of said portions 7 being greatest centrally of the ends thereof, and at the ends there being formed small angularly disposed web like portions 7', which serve as stiffening and reinforcing means, said blades extending inwardly from the rim part. 8 designates a hub part which may be secured to the end disk 2 in any suitable way.

55 The outwardly extending flange or flared portion 3 at the inlet side of the fan serves to stiffen and reinforce the structure at this point at one side of the stamped out portions, this outwardly flared end portion also increasing the inlet area of the wheel, increasing the capacity and efficiency of the wheel.

60 The wheels may be constructed from any suitable material, sheet tin plate or the like being considered especially adapted for the purpose.

65 The improved integral fan wheel pressed out from a continuous sheet of metal in accordance with my improved method of construction possesses the required strength and rigidity and can be manufactured at extremely low cost.

70 While a specific embodiment of the invention is illustrated in the drawing, I desire it to be understood that minor changes and modifications of the particular construction shown, and the carrying out of the invention in other forms, as will appeal to those skilled in the art and falling within the scope of

the appended claims, may be practiced without departing from the spirit of the invention.

What I claim is:

5. 1. A fan wheel member including a rim part constructed of sheet metal and provided with a series of transverse slits intermediate its edges and a series of short parallel longitudinal slits extending from the ends 10 of the transverse slits to points intermediate the same, the portions of the rim bounded by said slits being bent therefrom out of the curve of the rim, providing curved blade portions, and the intermediate parts of the rim 15 directly back of the ends of the longitudinal slits between the lines of said slits being bent centrally of their ends and at their forward portions out of the curve of the rim in the direction of the bend of the first mentioned 20 blade portions and having end portions extending at an inclination transversely of the

wheel at the ends of the first mentioned blade portions, said last mentioned end portions constituting stiffening means.

2. A fan wheel member including a rim 25 part constructed of sheet metal and provided with a series of transverse slits intermediate its edges, and a series of short parallel longitudinal slits extending from the ends of the transverse slits to points intermediate the 30 same, and the intermediate parts of the rim directly back of and adjoining the ends of said longitudinal slits being bent out of the curve of the rim and forming stiffening web portions at the ends of said blade portions. 35

In testimony whereof I hereunto affix my signature in the presence of two witnesses.

WILLIAM A. ROWE.
